CLAIM

The ornamental design for a skin adhesive decal for use with wearable medical devices, as shown and described.

DESCRIPTION

FIG. 1 is a top left isometric view of the skin adhesive decal for use with wearable medical devices;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top left isometric view thereof, showing the skin adhesive decal for use with wearable medical device in a condition of use with an unclaimed wearable medical device.

The broken lines showing the word “LOGO” depict portions of the skin adhesive decal for use with wearable medical device that form no part of the claimed design. The additional broken lines in FIG. 8 depict environmental subject matter that forms no part of the claimed design.

1 Claim, 6 Drawing Sheets
